UNITED STATES PATENT OFFICE.

WALTER W. VILNEAU AND ELBERT CHITTENDEN, OF PALO ALTO, CALIFORNIA, AS
SIGNORS OF ONE-THIRD TO HENRY E. JENSEN, ONE-THIRD TO WELLS P. GOOD-
ENOUGH, AND ONE-THIRD TO WALTER W. VILNEAU, ALL OF PALO ALTO, CALI-
FORNIA.

HARDWOOD-FLOOR-NAILING MACHINE.

REISSUED

Application filed June 13, 1927. Serial No. 198,472.

This invention relates to a hardwood floor nailing machine and its object is to drive a row of nails two at a time across the entire floor. It will be understood by those skilled 5 in the art that the ordinary hardwood flooring consisting of narrow strips about $\frac{3}{8}$ of an inch thick and two inches wide is first fitted tightly into the room. The workman then decides where he will place the several 10 rows of nails used for securing the hardwood to the pine floor base, whereupon he aligns the machine as he may desire and proceeds to drive a row of nails, two at a time, entirely across the floor. With the present 15 machine the first two nails can be driven very close to the wall and the machine is actuated to back away from the nails thus driven, which means that when the machine reaches the opposite side of the room that 20 it must be turned around and the nails driven into a dozen or more boards with the machine traveling in the opposite direction from which it has just come.

Another object of the invention is to drive 25 two nails at a time, one nail in each one of the two boards, and to provide a guide which will enable the workman to know at a glance that the machine is making the proper rate of speed each time it moves.

Another object of the invention is to provide 30 means whereby the shock of the hammer striking the nail drivers will be taken up by the spring of the floor rather than upon the frame of the nail driving machine, thereby making it easier upon the workman 35 and less wearing upon the frame of the machine itself.

Another object of the invention is to provide 40 means for feeding the nails into the nail chuck which will insure a constant line of nails in position to drop into the feeding tubes whenever the feed plate is shifted to the proper inclined position.

Another object of the invention is to provide 45 means whereby the amount of movement of the nailing machine can be varied to accommodate it to hardwood floor strips of different widths.

Another object of the invention is to provide 50 means whereby the operative can adjust a handle for the use of his left hand to a convenient position to steady the machine.

with that hand while he operates the driving mechanism with the other hand.

Another object of the invention is to provide 55 means whereby the frame moving means, i. e. the feeding device may be made operative at any given stroke or allowed to remain inoperative on any given stroke as may be desired.

Other objects of the invention will be apparent as the description proceeds.

An embodiment of the invention is shown in the accompanying drawings in which the same reference numeral is applied to the 65 same portion throughout the several figures of the drawings and of which there may be modifications.

Figure 1 is a side elevation of the complete machine showing it passing over an ordinary 70 hardwood floor with four nails already driven, and the driving mechanism ready to drive the next pair of nails in two separate boards.

Figure 1^a is a plan view of the front supporting base of the machine showing the application thereto of the gage.

Figure 1^b is a detail view of the latch 58 showing the pin 61.

Figure 2 is a front elevation of the complete machine with the gage omitted.

Figure 3 is a front elevation of the nail chuck and nail driving head with the driving head partly raised.

Figure 4 is a sectional plan of the supporting plate and nail chuck showing a portion of the lower end of the nail feeding tubes.

Figure 5 is a vertical sectional view through the nail hopper showing the arm 90 which raises and lowers to pick a string of nails from the heterogeneous mass of nails in the hopper whereby they are aligned for feed to the tubes and nail chuck.

Figure 6 is a plan view of the nail hopper 95 showing the pair of movable bars for picking up two rows of nails at a time.

Figure 7 is a vertical sectional view through the hopper on the line 7—7 Figure 6, to show the relation of the hopper sides 100 to the movable bars operating therein.

Figure 8 is a transverse vertical section of the device for dropping two nails at a time into the feed tubes and chuck,

Figure 9 is a front elevation of the nail feeder shown in Figure 8.

The machine comprises a frame consisting of two longitudinally extended bars connected by a front bar 3 and by the middle portion 4 of two braces 5 and 6, one on each side of the lower portion of the frame.

Connected to the base frame thus produced, are six vertically extending posts 7, 8, 9, 10, 11 and 12. The braces 5 and 6 are connected respectively to the posts 7 and 8 at their upper ends, and to the base members 1 and 2 at their rear ends. The base members are supported at their rear ends by the wheels 13 and 14. When in operation the machine rests on the wheels and on the cross bar 3 as shown in Figure 1, but when it is to be moved for the feed the nailing end of the machine is slightly lifted by a pair of feet 15 and 16 on opposite sides of the machine and supported by a bar 17. The bar 17 is pivotally mounted in an open slot 18 long enough to account for the usual movement of the machine from one position to another in the nailing of hardwood floors. An arm 19 extends from the cross bar 17 rearwardly to connect with the lower end of a vertically extending rod 20.

The weight of the rod 19 and rod 20 and machine is balanced by a long spiral spring 21 secured on its upper end on the back of the post 9 to effect the feed as will be later explained. The posts 9 and 10 extend vertically for about one half the height of the frame, and then incline sharply backward to about $\frac{2}{3}$ of the height of the frame and then extend vertically upward to about the same elevation as the posts 7 and 8, while just above their mid portion they are secured to the top of the two posts 11 and 12.

The posts 9 and 10 are offset at their uppermost portions as indicated at 22 to provide a pivot point for the pivot 23, said pivot consisting of a bolt extending from one post to the other post and for the support of a bell-crank 24 a pivot 23' is provided. A lever 25 is carried by the pivot 23 and it has a hand latch 26 at its operating end pivotally connected to a link 27 pivotally connected to another lever 28 mounted on the hand lever 25. A link 29 is pivotally connected to the lever 28 and to the bell-crank 24. The bell-crank 24 is in turn connected to a chain 30 which extends between two guide rollers 31, 32 on the rear end of the lever 25 and this chain is connected at its lower end to a lever 33 pivotally mounted at 34 on a lug 35 extended toward the nailing end of the machine from the post 10. This lever 33 is also pivotally connected to the upper end of the rod 20.

At the lower bend of the posts 9 and 10 there is a shaft 36 which supports the operating lever 37 which lever is connected at its back end to the rod 38 which rod is pivot-

ally connected in its turn to the hand lever 25 at its upper end.

The lever 37 has a depending lug 38 through which the screw 39 extends, and said lever is also provided with a slide lug 40. This slide lug is adjusted in position by means of the screw 39 passing therethrough, and this screw has a fixed nut 41 thereon to permit the screw to be rotated without changing its longitudinal position thereby properly adjusting the lug 40 which in turn adjusts the throw of the feed link 42, which link is pivotally mounted at 43 on the lug 40, both the lug and link being carried by the slotted lever 37.

At its lower end the link 42 is connected to a bell-crank 43 pivotally mounted at 44 to a depending lug 45 secured to the side brace 6 and the lower end of this bell crank is connected by a short link 46 to the bar 85 19 for an object presently to be explained.

Just at the back of the two posts 7 and 8 are two slides, 50, 51. These slides are secured to the back of the nail chuck supporting block 3 at their lower ends and to a solid cross bar 52 connected to the post 7 and 8 at the upper ends of the bars 50, 51. These bars have two cams 53, 54 thereon about the middle of their height, said cams tapering from the bottom wider upwardly. A slide 55 is secured between the two guides 50, 51 and it has a horizontally extended lug 56 at its lower end pivotally connected to the link 57 which latter is connected at its upper end to the lever 37. The slide 55 carries a depending latch 58 with a hook 59 to engage the underside of the hammer head 60 and the latch is so shaped that it has a horizontally extending pin 61 extending therethrough, which pin engages both of the inclined surfaces of the cams 53, 54 to release the hammer at the proper moment.

The plate 3 which forms the lower connecting mechanism between the rods 7 and 8 also forms the support for the nail chuck which consists of the two members 62, 63 between which the nails are dropped when they are to be driven into the floor. These members are held in their proper location by means of two light springs 64, 65. Two plates 66 and 67 are connected to the under cut recesses of the plate 3 to allow the two parts of the nail chuck to separate as much as may be necessary due to the passing therethrough of the nail drivers 68, 69. There are two holes through the plate 3 to receive the two nails and in addition there are two holes through the plate which receive the rods 70, 71, said rods having flat heads 72, 73 on their lower ends with striking heads 74, 75 on their upper ends. The object being to deliver the full force of the hammer 60 on the nails and thereupon to absorb whatever remaining force the blow may have on the heads 74, 75 which in turn 130

are supported by the flat heads 72, 73 of considerable extent resting upon the floor. The chuck 62 is pushed back by having the nail sets or nail drivers 68, 69 strike a flat 5 steel plate 76 which extends as a protection over the lower side of the two tubes 77, 78, and is connected thereto. The nail drivers will readily push both the chucks back the desired amount to allow the nails to be 10 driven and act the desired amount.

Both chucks are centered after the removal of the drivers by means of two screws 66, 67 extending through the corresponding bars 66 and 67 against which the chuck 15 members are pushed by the springs. The hammer head or striker 60 is connected to two side bars or guides 80, 81, said guides having their upper and lower ends outturned and notched to slide on the posts 7 and 8. 20 These slides also carry a cross bar 82 which extends in front of the posts 7 and 8 and which cross bar has lugs 83, 84 at its outer ends with suitable holes therein to receive the ends of the long spiral springs 25 85, 86. The lower ends of said spiral springs are connected to two outwardly extending studs 87, 88 secured to the ends of the plate 3, see Figure 2. The brass nail feed tubes 77, 78 extend from the top of the chuck up 30 to the individual nail feeder 89. This nail feeder consists of an outer casing 89 which has a slide 90 enclosed therein. This slide is reciprocated each time a nail is driven by 35 means of a lever 91, the lower end of which is shaped so it will be engaged by the hammer 60 when it rises and thereby cause two nails to be dropped into the nail chuck just before the hammer is released. The lever 91 is pivotally mounted on the post 8 at 40 93, and at its upper end it is connected by means of a small stiff spring 94 to the nail feeding slide 90. This nail feeding slide is so constructed that it will receive only two nails at a time, and whenever the slide is moved a short distance to the right, Figure 45 9, it will cause two nails to be dropped into the tubes 77, 78 to be delivered to the nail chuck. A spring 95 aids in restoring the feeder slide 90 to its desired position and 50 it will be seen that there is a groove 96 inside the casing 98 to allow the necessary lateral movement of the nail head and to permit it to drop off of the slide when it arrives at the position shown in Figure 10 where the casing is open enough to allow the nail to 55 pass into the tube. In the back of the casing for each tube there are four inclined rails 98, 99, 100, 101, a pair of nail feed slots being thus produced. Hinged to the members 60 98-101 inclusive, by mortised and recessed hinges are four oscillating hinge plates 102 to 105 which are connected to an operating arm 106 at their outer ends. These plates are sector shaped and operate 65 in the bottom of what is really a twin hop-

per. This arm 106 is connected to a link 107 which link is in turn pivotally connected to a lever 108. This lever is loosely mounted on the rod 36 and it is raised to the position shown in Figures 1 and 5 by means of a pin 79 109 which is engaged by the lever 37 when it lifts the hammer. The nail hopper is adapted to receive two or three pounds of nails at a time. It consists of the two side members 110, 111 which are connected to 75 the supporting bars 112, 113, the latter being carried by the posts 7 and 8. The hopper is circular on one side at 115 with slotted false bottom at 116 extending down over the movable feed bars. The false bottom 80 also has a movable retarding plate 117 slidably mounted on the plate 116 with notches 118, 119 to permit only one row of nails at a time to pass over each of the feed bars. The hopper sides 110, 111 have an inclined 85 portion and a vertical portion while the hopper bottom between the two movable feed bars consists of a single plate with two inclined portions 121, 122 and with two vertical portions 123, 124 in contact with the 90 vertically movable nail feeding bars. The result of the foregoing construction is that the nails will be agitated in the feed hopper and they will first slide one way and then the other, some nails always sliding forward 95 on the short feed bars 98 to 101 whenever there is space for them so to do.

The operation of the machine is as follows: Assuming the nail hopper to have had several pounds of nails placed in it and assuming the machine to have been operated several times to raise and lower the feeder bars 102 to 105 it will be ready to continue to proceed across the floor, and the operation is as follows.

The workman will stand at the back of the machine i. e. at the right of Figure 1, he will then grasp the handle 125 which screws into a slide 126 and he will set this handle at a suitable height on the post 7 for a man of his stature. He will then grasp hold of the lever 25 and handle 26 with his right hand. He will then tilt the machine slightly and roll it to the place where he wishes to begin work, the length of the machine extending transversely with respect to the length of the hardwood strips forming the floor. He then will align the machine as nearly as may be and place it so the gauge member 130 which consists of a wire yoke carrying some small rollers 131, 132, mounted in some projecting ears 133 to 136 in opposite ends of the supporting plate 3 over the crack between the last board being nailed and the next to the last board as indicated in Figure 1A which will bring the nailing position of the chuck to the adjoining edges of the two boards marked 137, 138 of Figure 1, i. e., the position for nailing as shown in that figure. Figure 1 shows the hammer raised and 130

within a short distance of being released by the two members 53, 54, and from the position shown. The operation is as follows:

- The workman will hold his hand steadily 5 on the handle 125 and will continue the downward movement of the handle end of the lever 25 holding the lever 26 close against the lever 25. The first action to take place will be the release of two nails to drop into 10 the nail chuck followed by the release of the latch which holds the hammer 60 by the cams 53, 54 whereupon the hammer will be pulled down by its springs 85, 86 with sufficient force to drive the nails and to finally 15 rest upon the tops of the heads 74, 75 as shown in Figure 2. At this same time the nail chuck members 62, 63 are forced apart sufficiently to permit the nail drivers 68, 69 to strike both nails and force them into the 20 floor with their heads well countersunk. During this time the workman has had the chain 30 pulled up slightly if he does not want to advance the machine. If he is ready 25 to start across the floor he will not put any pressure on the handle 26, with the result that immediately after the nails have been struck by the hammer that the spring 21 will lift the lever 19 enough to take the weight 30 of the frame on the two feet 15 and 16, and as the workman raises the lever 25 to re-engage 35 the hammer the bell-crank 43 will push on the link 45 sufficiently to move the entire nailing machine rearwardly the width of one board. The workman will verify the 40 position by looking at the gauge 130 to make sure that he does not drive any nails too close to the edge of the boards. The quantity of feed given at any time is determined by the proper setting of the screw 32. During 45 the time that the lever 37 is moving downwardly to re-engage the hammer 60 the lever 108 will also move downwardly until it reaches the stop indicated by the dotted line position of the hopper Figure 5 to stir up the body of nails and to collect a few 50 more nails between the feed bars 102—105 inclusive. These feed bars will then be forced upwardly as the hammer rises again until some of the nails carried by them slide 55 off onto the short feed bars on the left portion of Figure 5. At the same time two nails will be dropped on the transversely movable 60 slide 90 and those two nails will be dropped into the brass feed tubes 77, 78 as soon as the bar 80 strikes the lower end of the lever 91 and an instant prior to the hammer release.

Having thus described my invention, what I desire to secure by Letters Patent of the United States is as follows, but modifications may be made in carrying out the invention as shown in the drawings and in the above particularly described form thereof, within the purview of the annexed claims.

1. A floor nailing machine comprising a

frame, a nail chuck at the bottom of the frame, means to drop a pair of nails into said nail chuck, means to drive each of said nails into the floor over which the machine is placed, means to raise the front end of the machine, and means to automatically shift the entire machine a predetermined distance when so raised to drive a fresh set of nails at a new location.

2. A floor nailing machine comprising a frame, a nail chuck at the lower portion of the frame, means to drop a plurality of nails into said chuck, a vertically movable hammer adapted to strike the nails to drive them into the floor strips, means to lift one end of the machine following the driving of one set of nails, and means to automatically move said machine a predetermined amount when so lifted to a fresh position for nailing the flooring strips.

3. A floor nailing machine comprising a frame, a nail chuck carried thereby, a nail feeding hopper, means to drop a plurality of nails from the feeding hopper into the nail chuck, means to immediately thereafter release the hammer to cause it to drop on the nails and drive them into the flooring strip, means to raise one end of the machine as soon as the nail driving is completed, and means for shifting the entire machine to a new position for the driving of a new set of nails.

4. A floor nailing machine comprising a frame, wheels for the support of said frame at one end, a pair of movable feet to occasionally support the frame at the other end, a nail chuck adjacent the lower portion of the machine, a nail feeding hopper, means to deliver a plurality of nails from the nail hopper to the nail chuck, a vertically movable hammer, a swinging latch to engage and raise the hammer, means to raise the said latch from engagement from the hammer as soon as the nails have been dropped into the chuck, means carried by the hammer to engage and drive the nails, means to operate the frame supporting feet to lift the frame at one end after one set of nails has been driven, and means bearing upon the frame supporting mechanism to shift the frame to a position to drive a new set of nails.

5. A floor nailing machine comprising a frame, a nail chuck carried by the lower portion thereof, a gage adjacent the nail chuck, movable feet to occasionally support the machine adjacent the nail chuck, wheels to support the other end of the frame, a nail hopper, means to drop a plurality of nails into the nail chuck at predetermined times, a nail hammer, means to raise said hammer, springs to increase the rapidity of action and the blow struck by said hammer, means to release the hammer immediately after the nails have been dropped into the chuck, means thereupon to lift the frame of

the machine at one end, means to automatically shift the machine to a position for driving a new set of nails, and a series of manually operated levers at a convenient elevation for a workman to carry out the operation of the machine while standing at the side of the same. 5

6. A floor nailing machine comprising a frame, a chuck at the lower portion of the frame, means to feed nails into said chuck, a vertically movable hammer adapted to be dropped on the nails immediately after the nails have been dropped into the chuck, and a pair of movable floor stops supported by 10 the floor and upon which the hammer strikes after the nails have been driven home. 15

7. A nailing machine comprising a frame, a nail chuck at the lower portion of the frame, a nail feeding hopper vertically oscillating in said hopper to accumulate a plurality of arranged nails, means to raise and lower said bars, and individual feeding means consisting of a pair of inclined feeding bars and a horizontal plate, whereby a 20 plurality of sets may be dropped into the nail chuck, a vertically movable hammer carrying means to strike the heads of said nails, springs to increase the speed and action of said hammer, a latch for raising the 25

hammer, means to release the latch immediately after the nails have been dropped into the nail chuck, and a series of manually operated levers at a convenient height to enable a workman to operate the machine while standing at the side of it. 30 35

8. A nailing machine comprising a supporting frame, nail chuck at the bottom of the frame, a nail hopper at the top of the frame, means to feed nails to the chuck from the hopper, a slotted nail assemblying 40 bar pivotally mounted to be raised and lowered through the pile of nails in the bottom of the hopper whereby a series of nails are assembled thereon in an orderly manner, a shorter slotted bar to deliver nails to the individual nail feeding mechanism, means to operate the individual nail feeding mechanism latterly whereby the desired number of nails are dropped at one time, a hammer and means to drive the nails, and means to 45 drop the hammer upon the nail driving mechanism when the nails are dropped into the chuck. 50

In testimony whereof we have hereunto set our hands this 5th day of June, A. D. 55 1927.

WALTER W. VILNEAU.
ELBERT CHITTENDEN.
